CLAIM

The ornamental design for a medical device, as shown and described.

DESCRIPTION

FIG. 1 is a top, left, front side perspective view of a medical device according to a first embodiment of our new design;

FIG. 2 is a right elevation view thereof;

FIG. 3 is a left elevation view thereof;

FIG. 4 is a front side elevation view thereof;

FIG. 5 is a rear side elevation view thereof;

FIG. 6 is a top plan view thereof;

FIG. 7 is a bottom plan view thereof;

FIG. 8 is a top, left, front side perspective view of a second embodiment thereof;

FIG. 9 is a right elevation view of FIG. 8;

FIG. 10 is a left elevation view of FIG. 8;

FIG. 11 is a front side elevation view of FIG. 8;

FIG. 12 is a rear side elevation view of FIG. 8;

FIG. 13 is a top plan view of FIG. 8;

FIG. 14 is a bottom plan view of FIG. 8;

FIG. 15 is a top, left, front side perspective view of a third embodiment thereof;

FIG. 16 is a right elevation view of FIG. 15;

FIG. 17 is a left elevation view of FIG. 15;

FIG. 18 is a front side elevation view of FIG. 15;

FIG. 19 is a rear side elevation view of FIG. 15;

FIG. 20 is a top plan view of FIG. 15;

FIG. 21 is a bottom plan view of FIG. 15;

FIG. 22 is a top, left, front side perspective view of a fourth embodiment thereof;

FIG. 23 is a right elevation view of FIG. 22;

FIG. 24 is a left elevation view of FIG. 22;

FIG. 25 is a front side elevation view of FIG. 22;

(Continued)

FIG. 26 is a rear side elevation view of FIG. 22;
 FIG. 27 is a top plan view of FIG. 22; and,
 FIG. 28 is a bottom plan view of FIG. 22.
 The dot-dash broken lines represent boundaries of the claimed design and form no part thereof. All other broken lines illustrate portions of the medical device that form no part of the claimed design.
